UNITED STATES PATENT OFFICE.

WILLIAM H. REIFF, OF PHILADELPHIA, PENNSYLVANIA.

DESIGN FOR A SHOW-CASE.

Specification forming part of Design No. 5,461, dated January 2, 1872.

Specification describing a Design for a Show-Case, produced or invented by WILLIAM H. REIFF, of Philadelphia, county of Philadelphia, and State of Pennsylvania.

Design for a Show-Case.

The nature of my design is fully set forth in the accompanying drawing, in which—

Figure 1 represents a perspective view; Fig. 2, an end view; and Fig. 3, a rear view of the show-case.

The base A and top B of the show-case are rectangular, or nearly so, and the top is inclined downward toward the front, and is of smaller size than the base, to which it is connected by the front C, back D, and ends F F

of the case, all of these four sides being inclined, and narrowing toward the top, as plainly shown in the drawing.

I claim—

The design for a show-case, having its top and all four sides inclined, substantially as described, and as illustrated in and by the accompanying drawing.

In testimony whereof I have signed my name to this specification in the presence of two subscribing witnesses.

WM. H. REIFF.
